UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

CAR-DOOR-CONTROLLING DEVICE.

Application filed March 24, 1922. Serial No. 546,527.

This invention relates to car door controlling devices for controlling the car doors of passenger cars and more particularly of the electric traction type.

5 One object of my invention is to provide means whereby any one or more of a plurality of car doors may be operated by the manipulation of the same operating member.

10 Another object of my invention is to provide means for electrically controlling the operation of car doors.

Other objects and advantages will appear in the following more detailed description of the invention.

15 In the accompanying drawing; Fig. 1 is a diagrammatic view of a car door controlling equipment embodying my invention; and Fig. 2 a view of a modified form of the door controlling switch.

20 As shown in the drawing, the car door controlling equipment may comprise car door engines 1 and 2, the door engine 1 for controlling one car door, such as the exit door, and the other door engine 2, another door, such as the entrance door.

25 On cars equipped with two or more doors such as entrance and exit doors, it may be desired to open only one or the other door at one time according to the service conditions or at another time it may be desired to 30 operate both doors simultaneously.

Each door engine may comprise a casing having piston chambers containing pistons 3 and 4 connected by a piston stem 5 the movement of which is adapted to control the opening and closing of a car door in the usual manner. The piston 3 is the door opening piston, and is adapted to be operated by fluid under pressure to move the piston stem 5 in the direction for opening the car door, while the piston 4 is the door closing piston, adapted to be operated by fluid under pressure for moving the piston stem 5 in the direction to close the car door.

45 For controlling the admission and release of fluid under pressure to and from the pistons 3 and 4, electro-magnets 6 and 7 are provided, the electro-magnet 6 being adapted to operate double beat valves 8 and 9 for controlling the admission and release of fluid under pressure to and from the door opening piston 3 and the magnet 7 being adapted to operate double beat valves 10 and 11 for controlling the admission and release of fluid

under pressure to and from the door closing piston 4.

For controlling the magnets a contact drum 12 having a contact segment 18 may be provided, which may be associated with the usual motorman's brake valve device, so that the movement of the brake valve handle operates the contact drum. Interposed between the contact drum 12 and the operating magnets is a selector contact drum 13 having contact segments 14 and 15 and connected contact segments 16 and 17.

The motorman's brake valve may have the usual operating positions of release, lap, service, and emergency and the contact drum 12 may be adapted to so control the car door operating magnets that in release, lap, and service positions, the car doors will be closed, while in another service or brake applied position, the doors will be opened.

In operation, if it is desired to open and close both the exit and entrance doors simultaneously, the contact drum 13 is turned to the both doors position, as shown in Fig. 1. With the selector drum in the above position, if it is desired to apply the brakes and open the car doors, the brake valve and the contact drum 12 are turned to the position shown in Fig. 1, in which the contact finger 19, connected to current supply wire 20, engages contact segment 18, while the contact finger 21 also engages said segment. Electric current then flows through finger 21, wire 22 and contact finger 23 to the contact segment 15 of the selector drum. In this position of the selector drum, the contact fingers 24 and 25 also engage the segment 15 so that current flows through wire 26 to energize the magnet 6 and through wire 27 to energize the magnet 6'. The energization of magnet 6 causes the movement of the double beat valve 8 to its seat and the valve 9 to its open position in which fluid under pressure is supplied from the supply pipe 28, which is preferably connected to the emergency brake pipe for a reason which will hereinafter be explained, to piston 3, so that the piston 3 operates the piston stem 5 to effect the opening of the exit car door. In the same manner, the energization of magnet 6' operates to effect the supply of fluid under pressure to the door opening piston of the entrance door engine so as to cause the opening of the entrance car door.

100
105

The circuit wire 29 of magnet 7 and circuit wire 30 of magnet 7' are connected through the respective contact fingers 31 and 32 with contact segment 14 of the selector drum, but since the circuit of the current supply wire 33, which is connected to the segment 14 through finger 34, is open at the drum 12, the door closing magnets 7 and 7' will be deenergized and consequently the 10 double beat valve 11 of each magnet will be closed while the valve 10 will be open, so that the door closing piston 4 will be connected to the exhaust.

If the brake valve and the contact drum 12 are moved to any of the door closed positions shown, the circuit through the contact finger 21 will be opened, while the contact finger 35 will be connected through segment 18 with contact finger 19. Electric current 20 will then flow through the wire 33 to segment 14 of the selector drum and thence through the wires 29 and 30 to energize the door closing magnets 7 and 7'. The double beat valves 10 and 11 are then operated so 25 as to close the exhaust and open communication for supplying fluid under pressure to the door closing piston 4 of each door engine, so that both the exit and the entrance doors are closed. Since there is no current flowing 30 through the wire 22 to the segment 15, the door opening magnets 6 and 6' will be deenergized and the corresponding double beat valves 8 and 9 operated to connect the pistons 3 to the atmosphere.

If the conditions are such that it is desired to operate only the exit door, the selector drum 13 is turned to the exit door position. In this position, the door closing magnet 7' of the entrance door engine 2 is 40 constantly energized independently of the position of the door switch 12, since current flows from the supply wire 20 through wire 36 and finger 37 to segment 16 and thence through finger 32 and wire 30 to magnet 7'. The magnet 6' of the entrance door engine 2 remains constantly deenergized, since the finger 25 is out of contact with the segment 15 and as fluid under pressure is supplied 45 to the door closing piston of the entrance door engine by the energization of magnet 7', the entrance door will be held in the closed position.

The same connections, however, are maintained with respect to the magnets of the exit door engine as were made in the both door control position, the wire 33 being still connected to wire 29 through finger 34, contact segment 14 and finger 31, while wire 22 is connected to wire 26 through finger 23, segment 15 and finger 24.

It will therefore be clear that upon manipulation of the door switch drum 12 the exit door will be operated as in the case of the two door operation hereinbefore described.

If it is desired to operate the entrance door only, the selector drum 13 is turned to the entrance door position in which the door closing magnet 7 is maintained energized by the flow of current through wire 36, finger 37, contact 16, through the connecting portion to the segment 17 and through finger 31 to wire 29. The door opening magnet 6 is maintained deenergized since the contact finger 24, connected with wire 26, is not connected to a contact segment.

The magnet 7 being energized, the double beat valves 10 and 11 are positioned so as to supply fluid under pressure to piston 4 and thus operate the door engine to hold the 80 exit door closed.

The electrical connections of the magnets 6' and 7' are the same as those made in the two door position hereinbefore described, so that the entrance door may be opened and closed by the manipulation of the door drum 12, as will be evident, while the exit door remains closed.

When the motorman's brake valve is turned to emergency position, to effect an emergency application of the brakes, the pressure in the emergency brake pipe is reduced to atmospheric pressure and since the supply pipe 28 is charged from the emergency brake pipe, fluid pressure acting on 95 any of the door operating pistons of either door engine will be reduced to atmospheric pressure, so that the fluid on all the door control pistons being at atmospheric pressure, the pressures will be balanced, permitting 100 the doors to be opened or closed by hand.

Instead of providing a contact drum associated with the brake valve device as above described, a separate switch device may be 105 employed, such as the double throw knife switch 38, as shown in Fig. 2. This switch is connected so that in one position the wire 33 through which current is supplied for energizing the door closing magnets is connected to the current supply main 20, while in another position the wire 22 for supplying current to energize the door opening magnets is connected to the supply wire 20.

Having now described my invention, what I claim as new and desire to secure by Letters Patent, is:—

1. In a car door controlling mechanism, the combination with two door engines for controlling separate car doors, electric means for operating said door engines to effect the opening and closing of the car doors, and a controlling switch device for controlling the electric circuits for operating said electric means, of a selector switch having a position for completing the circuit through which one door engine is controlled by said controlling switch while the other door engine is operated to hold the corresponding door closed.

2. In a car door controlling mechanism, the combination with electrically operated devices for controlling the opening and closing of two car doors and a control switch for controlling the electric circuits of said devices, of a selector switch having positions for establishing the electric circuits between the controlling switch and either but not both of said electrically operated devices and another position for establishing the electric circuits to both of said electrically controlled devices.

3. In a car door controlling mechanism, the combination with electrically operated devices for controlling the opening and closing of two car doors and a control switch for controlling the electric circuits of said devices, of a selector switch having positions for establishing the electric circuits between the controlling switch and either but not both of said electrically operated devices and at the same time establishing a local

circuit for effecting the operation of the other electrically operated device to hold the corresponding door closed.

25

4. In a car door controlling mechanism, the combination with electrically operated devices for controlling the opening and closing of two car doors and a control switch for controlling the electric circuits of said devices, of a selector switch having positions for establishing the electric circuits between the controlling switch and either but not both of said electrically operated devices and at the same time establishing a local circuit for effecting the operation of the other electrically operated device to hold the corresponding door closed, and a position in which both electrically operated devices may be simultaneously controlled by manipulation of the control switch.

In testimony whereof I have hereunto set my hand.

CLYDE C. FARMER.
